PHONOGRAPH SHAVING COLLECTOR

Winton E. McConnell and Edwin L. Bracy,
Charlotte, Mich., assignors to Wilcox-Gay Cor-
poration, Charlotte, Mich., a corporation of
Michigan

Application September 28, 1948, Serial No. 51,597

1 Claim. (Cl. 274—47)

1

Our present invention relates to a combined shaving collector and more particularly to an improvement of the shaving collector inventions shown in Patent No. 2,351,948 and application Serial No. 757,135, both assigned to the assignee of the present invention.

More specifically, our invention relates to an auxiliary shaving collector secured to the cutting arm of a phonograph record cutter of the instantaneous recording type in order to enhance the shaving collecting action, thereby ensuring that the shaving cut from the record will gather properly around the spindle or around any shaving collecting tab which may be used on the record itself.

In instantaneous recording where a groove is cut in a record which is generally coated with a cellulose acetate material, the thread cut from the groove is thrown inwardly slightly by the action of the cutting needle. This thread normally tends to continue to rotate with the record and if left in position may foul the cutting needle as the cutting needle is driven inwardly.

The disclosures of the above-mentioned patent and application were directed to the provision of a flexibility mounted rubber collecting finger dragging lightly on the record surface just inwardly of the needle and engaging and holding stationary a portion of the thread so that when the other end of the thread was carried around the spindle by the rotation of the record, the thread would be caught on the spindle and wind up thereon.

The present invention contemplates the addition of an extra shaving collector placed further inwardly of the record surface than the first shaving collector providing an additional anchor for the thread cut from the groove, ensuring an even and rapid wrapping of the thread around the spindle and efficient collection of the thread.

In the prior shaving collector previously mentioned, the shaving collector unit was generally hung from the neck of the screw or bolt which fastened the cutting needle in the cutting cartridge. Since the cutting cartridge itself was flexibly mounted for vertical compliance, the shaving collector hung thereon also had some vertical compliance.

In addition, the shaving collector was so arranged that it was intended to drag slightly on the record and was thereby carried around so that it was inclined toward the center of the record.

This shaving collector in addition to tending

to hold the thread tended also further to throw the thread inwardly, thus enhancing the centripetal action of the needle on the thread.

The present invention contemplates securing a rigidly mounted rubber finger on the cutting arm unit radially inwardly of the initial shaving collector previously used and spaced so that its lower end is not over $\frac{1}{16}$ of an inch above the surface of the disc.

5 Furthermore, the additional shaving collector toward the center of the record tends to wind the thread tightly around the turntable spindle since it projects past the cutting area of the record covered by the original collector finger.

10 This leaves the entire playing area of the record free from threads which might catch the play-back needle and hinder play-back or automatic operation if used on automatic self-tripping equipment.

15 Any threads cut from the groove and thrown inwardly by the cutting action of the needle and by the action of the original shaving collector would thus be caught by the additional shaving collector and held stationary at the point of capture until the movement of the record carries another portion of the thread around the spindle resulting in a winding up of the thread.

20 Although the thread is a great deal smaller in diameter than $\frac{1}{16}$ of an inch, it nevertheless can be caught and held by a rubber finger spaced about $\frac{1}{16}$ of an inch above the surface of the record since the thread tends to curl and twist owing to the fact that it is cut sinuously from the sound track.

25 30 35 The primary object of the present invention, therefore, is the provision of a novel shaving collector for instantaneous recording instruments.

Another object of our invention is the provision of double shaving collector units for an instantaneous recording record cutter wherein both units are mounted on the cutting element of the instantaneous recorder with one of the units being mounted for some slight relative movement with respect to the cutting arm and the other 40 45 of the shaving units being mounted rigidly and having a definite shaving collecting position with respect to the cutting arm.

Another object of our invention is the provision of a rigidly mounted shaving collector on the cutting arm located inwardly of the cutting needle and positioned to act as a drag upon a thread cut from a groove in the record and thrown inwardly by the cutting needle.

50 The foregoing and many other objects of our

invention will become apparent in the following description and drawings in which:

Figure 1 is a view in perspective showing our novel combined shaving collector construction.

Figure 2 is an enlarged end view of the cutting arm showing the shaving collector elements mounted in position.

Figure 3 is a bottom view of the cutting arm showing the shaving collector elements in position.

Referring now to the figures, the cutting arm 10 is provided with a cutting head or cartridge 11 flexibly mounted therein in any suitable manner as, for instance, in the manner described in Patent No. 2,351,948.

The front of the cutting arm 10 has an opening 12 through which the screw or bolt 13 which secures the stylus 14 in the cartridge 11 is accessible.

The first shaving collector 20 is a generally triangular member of flexible rubber having a substantially pointed end 21 in contact with the surface of record 22, the wider end of the shaving collector 20 being provided with an opening by which it may be mounted on the screw 13.

The distance from the mounting opening of the shaving collector 20 and its pointed end 21 is slightly greater than the normal distance from the screw 13 to the record surface so that the shaving collector 20 will be inclined slightly inwardly radially of the cutting stylus.

If, when the record arm is placed on the record, the point 21 of the shaving collector 20 should be outside the stylus 14 or further away from the spindle 25 of the turntable, then the rotation of the record 22 in the direction indicated by the arrow will swing the shaving collector 20 in the direction of rotation of the record and around to a position where the shaving collector point 21 will be inward radially of stylus 14.

The shaving collector 20, therefore, as described in Patent No. 2,351,948 serves to exert a drag on any thread or shaving which may be thrown inwardly by the action of the cutting needle or stylus 14.

However, it sometimes occurs that the drag, especially owing to the flexibility and loose mounting of the shaving collector 20, is insufficient to hold the shaving with sufficient force to prevent its escape until two or three concentric shavings have collected.

Ordinarily, this poses no particular problem since the drag exerted by the shaving collector becomes effective at most after two or three revolutions and results in the winding of the shaving around the spindle 25.

However, in many instances it is desirable that the shaving be wound up on the spindle and away from the cutting stylus as rapidly as possible without any time delay. This is particularly so in automatic recording devices of the type shown in applications Serial Nos. 783,725 and 783,668 filed November 3, 1947, although it may be useful to avoid this occurrence in all types of recording.

For this purpose, the present invention contemplates the utilization of the additional shaving collector 30 rigidly mounted at 31 at the forward end of the cutting arm 10 and so arranged that its lowest end 32 is spaced about $\frac{1}{16}$ of an inch above the record surface 22.

Any shaving which is then thrown inwardly by the action of the cutting stylus 14 first has a drag exerted thereon by the point 21 of the shaving collector 20. As the portion of the shaving held by the record is pulled around toward the spindle 25

25, the additional drag of the additional shaving collector 30 becomes effective.

This is so even though the shaving collector 30 does not actually contact the record since the cutting of the thread or shaving along a sinuous path makes it twist sufficiently to be high enough to be engaged by the additional shaving collector 30.

If, as sometimes happens, the action of the cutting unit 14 is strong enough to throw the thread or shaving in beyond the point 21 of the shaving collector 20, then the shaving collector 30 comes into action and serves to capture the thread or shaving.

This is actually the primary advantage of the present invention in that the shaving collector 20 will usually engage the shaving cut during recording at low frequencies where the shaving may not be thrown inwardly more than one or two millimeters while the shaving collector 30 acts as a safeguard to capture and exert a drag on any shaving which may be thrown inwardly by the cutting needle to a greater degree, especially during recording of high frequency notes where the action of the cutting needle may be more violent.

As seen in the schematic view of Figure 1, the shaving collectors 20 and 30 exert a drag on the shaving or thread 40 so that as the record pulls the other end of the shaving or thread 40 through the positions of 40a, 40b, and 40c, the drag exerted by the shaving collectors 20 and 30 causes the shaving 40 to assume the position of a secant on an arc which rapidly increases in degree until the secant becomes a diameter and intersects the spindle 25, whereupon the shaving along the secant is pulled around the spindle 25 and begins to wind up thereon.

The shaving normally continues to wind up around the spindle 25 as the record rotates until the shaving breaks, whereupon the operation is repeated, the shaving collectors 20 and 30 exerting a drag on one end of the shaving until the other end of the shaving held by the record is pulled around the spindle 25 once more to wind up.

In actual practice we have found that the utilization of the compound shaving collectors 20 and 30 results in a clean record surface in which no shavings remain to mar the recording and in which the shavings are immediately captured and wound up on the spindle or other shaving collector element which may be used, thereby maintaining a record surface on which an accurate cut may be made.

However, it is to be understood that the inside shaving collector 30 may be used without the shaving collector 20 being used in combination as there will be a normal throw of the shaving inwardly from the cutting stylus 14 assisted, of course, by the rotation of the disc being cut dragging on the shaving. While it is preferred that the shaving collector 30 be resilient, satisfactory results are obtainable when it is rigid as of a piece of wire, for example.

In the foregoing we have described our invention solely in connection with specific illustrative embodiments thereof. Since many variations and modifications of our invention will now be obvious to those skilled in the art, we prefer to be bound not by the specific disclosures herein contained but only by the appended claim.

We claim:

A shaving collector means for an instantaneous disc recorder including a cutting arm, a turntable, and a spindle; a cutting stylus in the cutting arm engageable with a record disc placed over the

spindle on the turntable; said shaving collector comprising a resilient member rigidly secured to the cutting arm at a position inwardly toward the spindle with respect to the cutting stylus; said resilient member having an end projecting toward but spaced above the record surface by more than the diameter of a shaving; said resilient member exerting a drag on a portion of a shaving cut from the record; the record disc during its rotation pulling another portion of the shaving around until the shaving engages the spindle and begins to wind up thereon, and an additional shaving collector means comprising a resilient member swingedly hung on the cutting arm on a pivot located equi-distant from the spindle with the 15

stylus; said last-mentioned resilient member having sufficient length to engage the record surface at a position inwardly toward the spindle of the point of engagement of the stylus with the record.
